[57] CLAIM

The ornamental design for a table, as shown and described.

DESCRIPTION

FIG. 1 is a top perspective view of a table showing my new design;

FIG. 2 is a bottom perspective view thereof;

FIG. 3 is a top plan view thereof;

FIG. 4 is a side elevational view thereof, the remaining three side view being identical to that shown; and,

FIG. 5 is a bottom plan view thereof.

The characteristic feature of the design resides in the particular configuration of the table top as best shown in FIG. 3.
